APPARATUS FOR CASTING METAL

Joseph B. Brennan, Cleveland, Ohio

Application January 12, 1955, Serial No. 481,456

3 Claims. (Cl. 22—75)

This invention pertains to a method of casting and laminating metal and constitutes a continuation-in-part of my application Serial No. 202,707, filed December 26, 1950, now abandoned. According to this invention, molds in guided sequence are passed through a pool of molten metal, the molds being heated thereby and being filled with molten metal while immersed therein. After being filled with molten metal in, for example, a crucible with a pool of molten metal therein and by passing through said pool of molten metal, the molds in one example are passed through an externally embracing close-fitting cooling die preferably located underneath the crucible containing the molten metal. The molds may be conventional except that they have preferably a top and bottom gate and their sides are uniform in size.

According to one form of this invention, the molds have uniform exterior surfaces, and a uniform exterior cross-section, so that they will contact intimately and closely a passageway or guide through a molten metal pool and also through a cooling die. In the practice of this form of my invention, the mold preferably is made with an orifice leading through the exterior wall thereof, or with a series of orifices, or with openings defined by parting lines, or with top and bottom parting orifices where one mold abuts that one following and preceding it in passing through a pool of molten metal.

According to another form of this invention, the cavity of the mold is located on the exterior surfaces thereof, the cavity being formed as a depression in the exterior surface of the mold. In the practice of this second form of my invention, an exterior portion only of the mold need have a uniform cross-section, this characteristic being used to control the gauge of the finished casting and to aid in guiding the passage of the mold through a die for solidification of the metal in the mold.

According to still another form of my invention, there is no exterior or interior cavity, the mold being in the form of a solid mandrel, having a uniform exterior surface and uniform cross-section.

The molds may be made preferably of an investment such as zirconium oxide or molding plaster. Among other well known materials, core sand, molding sand binders, and carbon also may be used to make the molds. The cavities of the molds are preferably made by the use of volatile, meltable, or combustible models as is customary in the so-called lost wax process.

The molds are preferably heated or baked, and the model thereby removed prior to passage through the pool of molten metal. However, it is to be understood that the molds may be heated and baked and the model removed during the time of passage through the pool of molten metal, the model thereby being removed by the action of the heat of the molten metal itself.

This invention can be applied to making metal castings as described in application Serial No. 598,080, filed June 7, 1945, now issued into U. S. Patent No. 2,530,853. This invention is also useful in carrying out continuous casting as described in my copending application Serial No.

2

147,466, filed February 18, 1950, now Patent No. 2,714,235, granted August 2, 1955. This invention also may be used for many kinds of precision casting.

Other objects and advantages of the present invention will become apparent by the following description of preferred methods of practicing the art of my invention.

Referring to the drawings herewith:

Fig. 1 is a perspective view of a model used in carrying out the process of my invention in one of its forms;

Fig. 2 is a transverse sectional view of the model illustrated in Fig. 1;

Fig. 3 is a sectional view of a mold with model included therein, for use according to my invention;

Fig. 4 is similar to Fig. 3 except that, in this instance, the model shown and disclosed in Fig. 3 has been removed;

Fig. 5 is a transverse sectional view of the mold after the mold has been passed through a pool of molten metal;

Fig. 6 is a transverse sectional view of a model and metallic article to be laminated included therewith;

Fig. 7 is a sectional view of a mold with metal to be laminated and the model, as shown in Fig. 6, included therein, for use according to my invention;

Fig. 8 is a view similar to Fig. 7, except that in this instance the model has been removed therefrom;

Fig. 9 is a transverse sectional view of the mold, metal to be laminated, and laminated layer included therein;

Fig. 10 is a transverse sectional view of molten metal crucible and apparatus suitable for practicing the preferred forms of my invention;

Fig. 11 is a transverse sectional view of another type of mold suitable for use in the practice of my invention;

Fig. 12 is a transverse sectional view of a mold suitable for practicing the method of laminating a metal article in accordance with the teachings of my invention;

Fig. 13 is a transverse sectional view of a continuous mold similar to those shown in Figs. 11 and 12;

Fig. 14 is a transverse sectional view of a mold suitable to the manufacture of continuous tubing or pipe according to my invention;

Fig. 15 is a cross-sectional view taken on the line 15—15 of Fig. 14; and

Fig. 16 represents a sectional view of molten metal crucible and variable pressure apparatus suitable for practicing my invention.

Further referring to the drawings, Figs. 1 and 2 show a model generally indicated at 1, consisting, for example, of a die casting of conventional low melting point die cast metal, or wax, or easily combusted plastic, or other material such as is commonly used to make models for use in the so-called "lost wax" method of casting.

The model is accurately dimensioned in accordance with the dimension of the article desired to be produced. The only differences between the dimension of the model and that of the desired finished article are those resulting because of the shrinkage of the metal from which the final product is cast. By the use of my invention, this shrinkage is reduced to a low value because of the fact that additional molten metal is being fed into the mold while the metal therein is shrinking.

In addition to this peculiar advantage of my invention, the usual and well known procedure for determining the degree of shrinkage in the desired cast product is followed in determining the dimension of the die cast model 1.

The die cast model 1 is provided with a projection 2 extended therefrom at an appropriate point for the reasons hereinafter more particularly explained. For purposes of illustration, the gatings 15 and 16 shown and disclosed in Fig. 3 have not been shown as part of the model disclosed in Figs. 1 and 2, because these may be effected when the investment 3 is applied to the model 1.

After the die cast model has been provided, the surface

is freed from any burrs or other imperfections as, for example, the ridge or line left by the parting line of the die casting mold, or of other molds, used to produce such model. As illustrated in Fig. 3, the model 1 then is embedded in the investment 3, the investment 3 being of a heat-resisting oxide such as zirconium oxide compacted and having binders therein in accordance to well known practice. Any suitable investment material may be employed which, when molded about the model 1 and dried and baked and pressurized, will retain its shape in a substantially rigid and coherent manner with the projection 2 of the model extending through the investment 3 to the outer surface of the so-formed investment.

Fig. 3 illustrates the model encased in the investment 3, a groove or grooves 16 extending from the projection or extension 2 to the outer edge of the investment 3 to provide passageway for the ingress of molten metal. The projection 2 extends through the gate 16 to the outer surface of the so-formed investment. It is preferable also that an opening or a plurality of openings extend from the bottom of the investment 3 to the lower portion of the model 1.

Alternatively in place of the groove 16, extending from the projection or extension 2 to the outer edge of the investment 3, and opening 15, at the bottom of the investment 3 and extending to the lower portion of the model 1, it is possible to make the model 1 in such a manner that the model has extensions which correspond to the openings or grooves 15 and 16 and which project through the bottom surface of the investment 3 as shown, and which also extend to the exterior of the outer periphery of the investment 3 in Fig. 3 as shown, thus to replace and fill and define the grooves 15 and 16 when the model is removed.

After the model 1 has thus been embedded in the investment, as illustrated in Fig. 3, the latter is heated to a temperature sufficient to melt the material from which the model is made or sufficient to ignite the model so that it can be burned out. Fig. 4 illustrates a mold which previously had included therein a model which now has been removed, as is common practice in precision casting. The melted model, if of melttable material, is then drained out of the investment through openings 15 and 16, leaving therein a cavity 4, Fig. 4, there being a passage 5 which extends from the cavity 4 to the outer surface of the mold at the point formerly occupied by the projection 2 of Fig. 3. Also an opening 15 extends from the cavity 4 to the bottom surface of the mold as explained above.

After the mold has been thus prepared as illustrated in Fig. 4, the investment 3 with the cavity 4 therein is ready for use as is later to be explained.

My invention is also especially adapted to the production of composite metallic articles as, for example, a sleeve bearing having an outer reinforcing and supporting part of steel and an inner layer of cast bearing metal adhering to and supported by the steel body.

In carrying out this modification of my invention, the pattern generally indicated at 8 in Fig. 6 will consist of the component 9 which is also the component of the desired finished article and the lamination 10 of melttable or burnable material. The model generally indicated at 8 is provided by incorporating the component 9 with a die casting 10 which is formed of low melting point die cast metal or wax or plastic material, with projection 11 extending therefrom, projections corresponding to the openings or grooves 15 and 16, Fig. 7, also extending therefrom if desired.

The model 10 and the component 9 as illustrated in Fig. 6 are embedded in an investment mold 12, Fig. 7, formed in the manner previously indicated, after which the mold is heated sufficiently to melt away or to burn away the die casting 10 and thus to permit draining or removal from the mold of the metal, plastic, or wax die casting 10 leaving a cavity generally indicated at 13 in

Fig. 8 having openings 15 and 16, Fig. 8, extending therefrom, the projection 11 of Fig. 7 representing the appropriate portion of the opening 16 of Fig. 8.

Again for purposes of illustration, the gatings 15 and 16 shown and disclosed in Figs. 7, 8 and 9 are not shown in the model disclosed in Fig. 6, it being possible to make the model with a gating corresponding to the openings 15 prior or subsequent to the enclosure in the investment 12.

Instead of the investments 3 or 12 shown in the drawing, it is possible according to this invention to use multiple-piece permanent molds, as of metal or graphite or aluminum oxide, which are pre-formed and which can be parted after the casting has been made therein, it being possible to use these molds over and over again.

In carrying out my invention, a series of exteriorly similar investment molds 3 are stacked, as is shown in Fig. 10, in alignment over and inside of the perforate guide tube 17 as of graphite, which guide tube has openings 17a through and about its cylindrical wall, and which guide tube 17 is surrounded by the molten metal pool 22 in the curcible 21, heat being supplied thereto by the high frequency coils 19.

I apply pressure to the topmost mold 3 and thereby force the stacked molds through the sleeve 17 and the close-fitting die 20 and through the aligned cooling die 18, so that the metal, by passing through the groove 16 into the molds 3, forms the casting 24 therein as the molds are forced down through the molten metal 22. After the castings 24 are made, they are passed along and chilled by the cooling die 20 with the cooling coils 18 therein and ejected at the bottom of the cooling die 18 as solid metal 6.

The casting 24 then is had by removing thereafter the investment 3 therefrom. It may be noted that, in the example illustrated by Fig. 10, the investment molds 3 do not have the openings 15 extending from the bottom of the cavity 23 to the exterior surface of the investment 3. Where the openings 15 are employed, they are substantially in alignment with the opening 7 or 14 of the next preceding investment mold 3.

Where molds similar to those described in Figs. 1 to 9 inclusive are employed in the practice of my invention, Figs. 5 and 9 represent the finished product wherein the molten metal of the pool has filled the cavity of the mold to form the finished product. In Fig. 5, the finished casting 6 has gatings 15a, 16a and 5a corresponding to the openings 15, 16 and 5 of Fig. 4. In Fig. 6, the component metal 9 and the laminated layer 10 constitute the finished pattern. In this latter instance, the laminated layer has gatings corresponding to the openings 15 and 16 of Fig. 8.

Figs. 11, 12, 13 and 14 illustrate various other modifications of molds or shapes suitable to the practice of my invention. In Fig. 11, the investment mold generally indicated at 25 has a sleeve 28 extending therefrom, the sleeve 28 fitting into the hollow portion 27 of the next preceding mold 25. The portion 26 of the mold 25 has a uniform exterior surface and a uniform cross-section.

The molds 25 are passed continuously and successively fitted together through a guide tube into a pool of molten metal and through a cooling die in a manner similar to that previously described with reference to Fig. 10, the metallic sleeve 30 thus being cast around and about the recessed portion 29 of the sleeve 28.

The uniform exterior cross-section and uniform surface at the portion 26 in the mold 25 acts as a guide and alignment agent in the passage of the mold 25 through the guide tube and through the cooling die. The gauge or the dimension of the metallic bushing or sleeve 30 is determined by the distance between the surface 29 of the mold 25 and the exterior of the surface 26.

In the practice of the modification, the mold 25 again may consist of any refractory material such as graphite or the like, or it may consist of a destructible investment

material, the material suitable for use in the investment 3 and 12 being satisfactory to the construction of the mold 25. Preferably in the modification illustrated in Fig. 11, a destructible material is not used, and the individual units 25 may be used over and over again.

In Fig. 12, many of the parts are identical to those in Fig. 11 and are described by like numbers. In Fig. 12, a component metallic sleeve or bushing 31 is first placed around the surface 29 of the mold 25. The molds are then passed in sequence through a guide tube into a pool of molten metal and through the cooling die in a manner similar to that described in reference to Fig. 11. However, in this instance, the finished cast product 33 consists of the component metallic sleeve 31 and the laminated layer 32 thereover and bonded thereto.

The gauge or the dimension of the lamination 32 in this instance is determined by the distance between the exterior surface of the component metal 31 and the extension of the surface 26.

In Fig. 13, I have shown a continuous destructible investment mold material wherein the mold indicated at 34 has the external projections indicated at 35 and wherein the metal is cast about the surface 36 of the mold 34 to form the finished ring casting 30. Here again, the dimension of the finished product 30 can be controlled in a manner similar to that previously described with reference to Fig. 11. In the practice of the modification of my invention shown in Fig. 13, a destructible mold material is desirable in order that the finished casting 30 may be removed from the mold.

In Figs. 14 and 15, I have illustrated a mandrel 37 about which is cast the tubing 38. In the practice of the modification shown in Figs. 14 and 15, accurate splines are employed in the guide tube in order to control the thickness of the tubing 38 and the alignment of the mandrel 37. In other respects, the method of passing the mandrel 37 through the guide tube into the molten metal and through the cooling die is much the same as that described in reference to Fig. 10.

Where a continuous tubing is to be cast, the splines must be located in the guide tube above the point where the metal tube 38 solidifies. Where it is desired to cast strips of metal about the mandrel in preference to a tubing, the splines are extended into the cooling zone in accordance with the width of the strips which it is desired to secure, the widths of the strips being defined by the distances between the splines.

In order to aid in the withdrawal of the strips through the die, a clearance may be allowed between the splines and the mandrel to an extent that a thin fin is cast between the strips. The existence of these fins enables the casting to hug the mandrel and thus lessen the amount of pulling and the tension means which may be required to draw the strips from the die. The mandrel 37 may be made of any suitable mold material in accordance with the principles herein previously explained.

The metal in and around a given section of the mold or form preferably should be liquid prior to the entry of that section of each mold or form into the solidification zone in order that shrinkage and solidification is effected solely in the solidification zone. Thus, preferably at the entrance to the solidification zone, the liquid metal continues to be fed into the connected cavity of the mold at this point so that the mold cavity is substantially full when it passes out of the solidification zone and a casting completely filling the mold cavity is obtained, which is desirable. Of course, in those cases where the mold cavities are not continuous and connected, the metal will not continue to feed after the mold opening has entered the solidification zone.

I have described casting previously in my application Serial No. 147,466, filed February 18, 1950. Insofar as common subject matter is involved, this application constitutes a continuation in part of this prior application.

According to this invention, it is also contemplated to apply pressure such as gas pressure to the molten metal pool when it is being applied to the mold. This can be done by enclosing the apparatus of Fig. 10, all except 5 the outlet portion thereof, in a pressure crucible device such as is described in my Patent No. 2,371,604.

If desired, the mold with the models therein may be made by continuous extrusion methods, cured by high frequency heat with thermo-resins, as binders and with 10 cut interruption passed through the pool of molten metal, the cavities being filled thereby. Or, if chosen, divided multiple-piece molds may be used so long as they will suit the conditions. For example, a two-piece mold may be made and used according to conventional plaster or 15 ceramic or permanent mold practice which will preferably conform where necessary to the cooling die inside surface and dimensions.

By my invention, metal of constant or varying cross-section may be produced continuously if a model, as an 20 extrusion of plastic or wax or combustible material, is provided which may be surrounded with ceramic mold material and then have the model evaporated or burnt out or otherwise removed, whereafter the metal fills in the cavity as the so-provided mold is passed through the pool of molten metal. It is possible to use divisible molds of 25 metal or ceramic material such as graphite which may be stacked and/or fastened together in aligned relation and which may be re-used after emptying of their castings.

It is possible by my invention to make castings as accurate as any obtainable by the so-called centrifugal lost-wax method or by more crude methods, also to do so continuously and save much labor and energy and material thereby.

It is also possible to make laminated metals in strip 35 form or in individual piece form by my invention. The base metal as well as the investment containing same becomes heated by my invention so that a good bond is obtained. Thus, steel and copper, or steel or silver can be well bonded.

To make a strip of laminated steel and bronze, the model should be a ribbon, for example, of steel faced with a layer of combustible or volatile or meltable material, such as tin and/or lead or plastic model material which, when invested and cured and run through the pool of molten metal, will be heated and faced thereby with the metal of the molten metal pool replacing the model.

The fact that the investment becomes very hot in my 50 process facilitates degassing and flow through tiny orifices so that very little metal is used in gating. Very thin castings, for example, ribbon metal 0.003" thick or less, can be made by my process if a removable ribbon of 55 similar thickness is used as the model and continuously invested and passed through my apparatus and filled with molten strip metal due to the fact that the investment mold is so hot as to equal the temperature of the metal being cast.

It is of considerable value in some cases to have the 60 cavities 23 in stacked molds 3 aligned and interconnected on top of each other so that there is a movement of metal downward toward the chill zone in addition to the normal flow to fill the cavities because of degassing caused by progressive and constant chill as in a string casting.

Fig. 16 illustrates a variable pressure chamber generally indicated at 39 in which is enclosed the crucible 40 containing molten metal 41 therein. Gas pressure is supplied to the variable pressure chamber 39 through the gas inlet tube 42. Alternatively, the inlet pipe 42 may 70 serve as an outlet pipe, and the air of the atmosphere or other gaseous impurities may be removed and a vacuum created in the variable pressure chamber 39.

If desired, an inert gas may then be supplied to the chamber 39, where it is desired to cast under a pressure other than that of a vacuum. In this manner, oxygen-free

metal may be cast with the apparatus of my invention. The gas pressure gauge 43 accurately registers the amount of pressure in the chamber 39, and the pressure in the variable pressure chamber 39 can be regulated in accordance with the pressure desired by the use of a shut-off valve (not shown) in combination with the gas inlet pipe 42.

The metal 41 in the crucible 40 is maintained molten by means of the electro-conductive coils 44 connected to the external circuits 45 and 46 and are maintained in pressure-sealed relationship with the variable pressure vessel 39 by means of the conduits 47 and 48.

The mandrel or mold 49 is moved through the packing gland seal 50 located in the detachable top plate 51 of the variable pressure crucible 39, and into the molten metal 41 by way of the guide tube 52 having therein the perforations 53. The molten metal flows through the perforations 53 in the guide tube 52 and around the mandrel or mold 49. As the mandrel or mold 49 moves downward through the die 55, which is cooled by a cooling fluid flowing through the coils 56, a solidification of the molten metal 41 is effected and the solid casting 54 thereby is obtained.

The detachable top plate 51 is secured to the lower portion 56 of the variable pressure chamber 39 by means of the bolts 57. Thus, when the supply of molten metal in the crucible 40 is to be replenished, the top plate 51 may be removed from the lower portion 56, thereby permitting access to the interior of the pressure chamber 39.

The mechanism of Fig. 16 may be varied in accordance with various of the modifications previously explained with reference to Figs. 1 to 15. For example, the splines 57 of Fig. 16 are employed much in the manner previously set forth. Again, by way of illustration, the apparatus of Fig. 16 may be used in conjunction with a mold having a cavity on the interior thereof, in a manner similar to that described in reference to Figs. 11, 12, and 13. Or the mold may have therein a depression cavity, as is again shown in Figs. 11, 12, and 13.

Further, rather than the mandrel or mold 49, the mold 3 of Fig. 4, or the mold 25 of Figs. 11 and 12, or the mold 34 of Fig. 13 may be substituted in place thereof. Still other modifications herein disclosed may be employed in the apparatus of Fig. 16, it also being possible for example, to secure a laminated casting by the practice of the method therein disclosed.

If desired, the constancy of the pressure may also be aided by maintaining a constant head of metal 41 in the crucible 40 by the use of a feed crucible located externally or internally of the pressure chamber 39.

Impurities, such as oxides, can be reduced and converted into pure metal by bubbling a deoxidizing gas, such as carbon-monoxide, through pipes 58.

Upon release of gas into pipes 58, the shut-off ball valve 59 is released upward by the pressure of the gas to permit the flow thereof into the crucible 40 and through the molten metal, the ball valve 59 being retained in its upward position by the guard 60. The ball valve 59, in this illustration, is of a weight greater than that of the molten metal which it displaces. When, in this example, the gas flowing into pipe 58 is shut off, the ball valve 59 closes the pipe outlet and thus prevents a backward flow of molten metal into pipe 58.

The use of a vacuum is also possible in the practice of my invention. For example, the inlet pipe 42 may be used to create a vacuum in the variable pressure chamber 39, thus to remove gaseous impurities from the molten metal or to eliminate the presence of free oxygen in the pressure chamber. After the creation of a vacuum

in the variable pressure chamber 39, the pipe 42 may be employed to admit an inert gas into the chamber, thereby to create a desired pressure for casting purposes.

Although I have described my invention in terms of metal casting, it is to be understood that the principles of the invention may be applied and the objects thereof may be achieved in the casting of ceramic materials, quartz, mica, germanium, silicon, glass, and other fusible materials, as well as in the casting of metal.

10 Other modes of applying the principle of the invention may be employed, change being made as regards the details described, provided the features stated in any of the following claims, or the equivalent of such, be employed.

15 I therefore particularly point out and distinctly claim as my invention:

1. A casting apparatus comprising a downwardly extending tubular mold guide, an adjoining downwardly extending cooling die below and aligned with said guide, 20 a mold of substantially the same cross-section size and shape as said guide and die adapted to be moved downwardly through said guide for filling with molten material and through said die for cooling of said mold and solidification of the material therein, and a molten material supply crucible around said guide, said guide being formed with an opening through which molten material flows from said crucible into said mold when the latter is disposed within said guide, said mold when thus disposed within said guide and when moved downwardly through said cooling die constituting a closure for said crucible.

2. The apparatus of claim 1 wherein a series of superimposed molds of such cross-section size and shape are successively moved downwardly through said guide and said cooling die for filling with molten material and for solidification of the material therein.

3. A casting apparatus comprising a downwardly extending mold guide, an adjoining downwardly extending cooling die below and aligned with said guide, a mold 40 guided by said guide and die for movement downwardly through said guide for filling with molten material and through said die for cooling of said mold and solidification of the material therein, and a molten material supply crucible laterally adjacent said guide, said guide being 45 formed with an opening through which molten material flows from said crucible into said mold when the latter is disposed in said guide, said mold and said cooling die being of substantially the same cross-section size and shape whereby said mold and solidified metal when 50 moved downwardly through said cooling die constitutes a closure for said crucible.
